(57) **CLAIM**

The ornamental design for a support for flat panel monitor display unit, as shown and described.

DESCRIPTION

FIG. 1 is a perspective view of a support for flat panel monitor display unit, incorporating the new design.

FIG. 2 is a front elevation of the support for flat panel monitor display unit of FIG. 1.

FIG. 3 is a rear elevation of the support for flat panel monitor display unit of FIG. 1.

FIG. 4 is a left side elevation of the support for flat panel monitor display unit of FIG. 1.

FIG. 5 is a right side elevation of the support for flat panel monitor display unit of FIG. 1.

FIG. 6 is a top plan of the support for flat panel monitor display unit of FIG. 1; and,

FIG. 7 is a bottom plan of the support for flat panel monitor display unit of FIG. 1.

1 Claim, 6 Drawing Sheets
